TICKET-STRINGING APPARATUS

Jacob F. Graeber, Norristown, Pa., assignor to
The National Tag Manufacturing Corporation,
New York, N. Y., a corporation of New York

Application December 10, 1929; Serial No. 412,978

20 Claims. (Cl. 93—91)

This invention relates to apparatus for applying strings to tickets, and has for an object the provision of apparatus which will apply strings to a plurality of strips of tickets simultaneously, which will operate easily and effectively and do its work without marring the tickets.

The enumerated and various other objects and features of novelty will be apparent from the following description of an illustrative embodiment of the invention when considered in connection with the accompanying drawings in which

Figure 1 is a top plan view;

Figure 2 is a front elevation;

Figure 3 is a right side elevation;

Figure 4 is a left side elevation;

Figure 5 is a rear elevation;

Figure 6 is a longitudinal vertical section taken approximately on the line 6—6 of Figure 1;

Figure 7 is a longitudinal vertical section taken approximately on the line 7—7 of Figure 1;

Figure 8 is a transverse vertical section taken on the line 8—8 of Figure 6;

Figure 9 is a transverse vertical section taken on the line 9—9 of Figure 6;

Figure 10 is a horizontal section taken on the line 10—10 of Figure 9;

Figure 11 is an interior elevation partly in section taken approximately on the line 11—11 of Figures 7 and 13;

Figure 12 is a transverse vertical section taken on the line 12—12 of Figure 13;

Figure 13 is a horizontal section taken on the line 13—13 of Figure 3;

Figure 14 is a partial longitudinal vertical section on the line 14—14 of Figure 1 but showing the parts at a different stage of operation.

Figure 15 is a partial longitudinal vertical section taken on the line 15—15 of Figure 8 but showing the parts at a different stage of operation.

Figure 16 is a partial longitudinal vertical section taken on the line 16—16 of Figure 1;

Figure 17 is a top plan view of one of the knotters employed in the apparatus.

Figure 18 is a horizontal section on the line 18—18 of Figure 19;

Figure 19 is a front elevation of parts shown in Figure 17;

Figure 20 is a vertical section taken on the line 20—20 of Figure 17 but with the spindle rotated slightly.

Figure 21 is a vertical section taken on the line 21—21 of Figure 17; and

Figure 22 is an elevation of the cam taken on

the line parallel with but behind the line 21—21 of Figure 17.

The apparatus employed herein is adapted to insert strings through the ends of each of a strip of tickets such as price tags and the like. The strings are intended for attaching the individual tickets when separated from the strip to articles which are to be marked. The strings are, as usual in this type of tag, formed in a loop by tying the ends of the string together after it has been passed through the ticket.

The present mechanism in performing this service of applying strings to a plurality of tickets in a strip utilizes the following operations. In naming these operations there is no intention to limit the apparatus to such exact operation but the same is given merely by way of fully explaining the exemplary apparatus which has been chosen for description.

The tickets are placed in a stack between vertical guides in the machine. Beneath this stack operate slides which have suction openings in their top surfaces and ducts leading therefrom through which air may be exhausted to a suction pump. The slides when moved back beneath the stack of tickets pull the lowermost ticket strip tightly down upon the slides. Thereafter the slides move forward together with the ticket strip adhering thereto to push it forward beneath a row of needles. The needles insert strings through partially made holes in the tickets and grippers disposed below the table top grasp the ends of the strings as the needles start to withdraw. The feed slides then retract and a ticket clamp which previously had been raised by a wedge member traveling with the slides is allowed to drop to grasp the tickets. During the downward movement of the needles the strings are prevented from pulling back through them by an upper string gripper which binds the strings against the upper ends of the needles. Means is provided for operating this upper gripper so as to release the strings at certain times when gripping is not desired.

When the needles have been raised again a plurality of strip grippers disposed on a swinging pull frame move over toward the needles and grasp the tickets. The pull frame then moves away from the needles carrying with it the strip of tickets causing the strings to lengthen by being pulled out through the needles from a source of supply, the lower ends of the strings at this time being held by the lower string grippers. When the pull frame has moved back to its extreme position means associated with the pull frame

but mounted on a stationary frame in front of the main frame of the machine acts to restore the tangs or burrs made by the needles passing through the tickets. This means may be termed the tang restoring means. It consists of separable members of which the lower may be termed anvils and the upper, punches. These members are disposed between the strip grippers and meet exactly at the needle holes when the frame is in this extreme position.

Following this action rotary knotters rotate to place a loop in each doubled strand of string attached to the tickets. In connection with the knotters, there is an upward swinging bar for raising the strings in front of the knotters. This causes the rear end of the strings to be caught in the jaws of the knotters which open during their rotative movement for the purpose. At about this time scissors sever the strings behind the knotters and as the loop is formed the pull frame moves toward the knotters to allow slack for same. After the knots have been formed the pull frame is moved forward away from the knotters so as to tighten the knots, the ends of the severed strings being still held in the jaws of the knotters. Shortly after this, the knotters release the strings and ticket strip grippers on the pull frame open to release the strips. Then a sweep swings downward along the front of the machine between the pull frame and the knotters to throw the strip of tickets out of the machine. In this operation the string attached to the ticket on one end of the strip is pushed downward in a groove or space between two plates and supports the strip of tickets along with other strips which have previously been stringed.

In general, and according to Figures 3 and 4 the apparatus comprises a base 20 supporting a main frame 21, a front frame 25, and toward its rear end supporting drive and control mechanism. The main frame includes a table 22 and the front frame includes spaced columns 26 connected at the top by a head 27. The driving means comprises, as shown in Figure 1, a suction motor 39 connected independently to a source of power and utilized for driving a suction pump 31 (see also Fig. 3) through a belt 32 and a main drive motor 35.

The main motor 35 is provided with a control box 36 whereby it may be started and stopped and, if desired, its speed regulated. Through a belt 37 the main motor drives a worm shaft 38 having a worm meshing with and driving worm gear 39 secured upon a stub shaft 40 mounted in bearing brackets 41 secured to the base 20. Mounted upon the main frame of the machine there is a short jack shaft 42 provided with weighted hand wheel 43. The stub shaft 40 and the jack shaft 42 are provided with keyed pulleys 44 and 45 respectively, and idler pulleys 46 and 47 fast on the stub shaft and loose on the jack shaft respectively. A belt 48 forms the power transmitting medium between the two shafts.

Still referring to Figure 1 the jack shaft is provided with a pinion 50 driving a gear wheel 51 fixed on the main shaft 52. As viewed in Figures 3 and 6 the main shaft rotates in a clockwise direction. It constitutes the principal origin of motion for the various parts of the machine. The main shaft drives a secondary shaft 53 in its own direction of rotation (Figures 3, 6 and 7) through sprockets 55 and 56 on the main and secondary shafts, respectively, operatively connected by a sprocket chain 58. An adjustable tightener 59 is secured to the base of the ma-

chine in position for a roller 60 thereon to be pressed against one span of the chain.

As viewed in Figure 8 the main shaft carries (from left to right) a string lift cam 61, a knotter rack disc 62, a needle cam 64, the secondary shaft drive sprocket 55, a pull frame cam 65, a feed slide eccentric 66, a bevel gear 67 supplying power to the scissors, a lower-string-gripper cam 68 and an upper string-gripper cam 69.

As shown in Figure 2 the secondary shaft 53 is provided at a distance from each end with a pair of toggle arm cams 71 for operating the tang restorers, at the right end with a sweep cam 72, at about the center with a pull frame cam 73 and to the right of this with a strip grip- per cam 74.

Feed slides

Referring to Figures 1 and 6 the channel-shaped vertical guides 79 are adapted to hold a stack of ticket strips. Beneath this stack of strips two spaced slides 80 for opposite ends of the strips operate. The slides have suction openings 81 at their front ends and on the upper surface thereof. These openings are connected to ducts 82 which may be formed as bores inside the slides but in the present instance are merely formed as grooves on the lower side of the slides.

As shown in Figure 6 the ducts 82 are closed toward their rear ends by strips 83 secured to the under surfaces of the feed guides. A nipple 84 connected to the duct 82 is rigidly mounted on each slide and is connected by flexible tubes 85 with the suction pump so that suction may be created at the openings 81 at all times.

The slides are retained firmly upon their guideways by a guide-wedge 86 having set screws 87 which serve to hold the slides upon the table sufficiently tight to prevent leakage from the ducts 82. As shown in Figures 1 and 13, the slides are connected by a crossplate 88 to which is attached a wedge 89. As shown in Figure 7 the wedge is employed to lift a ticket clamp strip later to be described.

Toward their rear ends the slides are provided with depending lugs 91 operating in slots 92 formed in the table. To these lugs connecting rods 93 are attached by pins 94. At their other ends the rods are connected by pivot pins 95 to rocker arms 96 secured upon a rocker shaft 91. Also secured to the rocker shaft (see also Fig. 5) is a slotted arm 98 connected by an eccentric rod 99 with the eccentric 66 secured on the main shaft.

Ticket clamp

As best shown in Figures 7 and 13, this clamp comprises a flexible strap 101 longer than the ticket strips secured just behind the needles to the table by screws 102. The strap is provided with several forwardly extending fingers 103 adapted to press a ticket strip at several places upon the table. As stated above, the strap is raised each time the feed slides move forward with a ticket strip by the wedge 89 to allow the strip to move forward beneath the strap to operating position beneath the needles.

String inserting needles

In Figures 6 and 11 there is shown a plurality of needles 105 secured to a needle-bar 106 extending across the frame and guided by vertical rods 107 secured at their lower ends to the table and braced at their upper ends by a tie-bar 108 rigidly connected to and moving with

the needle-bar 106. The needles may be individually secured to the needle-bar 106 by clamps 109 and clamp screws 110.

The needles in the present instance are tubular and the strings pass through them. Strings are fed to the upper ends of the needles from several sources of supply (see Fig. 2) through a plurality of tubes 111 clamped to a plate 112 supported upon column 113.

As shown in Figures 6, 9 and 11, the needle bar at each end carries a pin 115 engaged by arms 116 loosely mounted (see also Figure 13) to a transverse shaft 117 mounted in bearings 118 secured to the top of the table.

One of the arms—the left in Figure 13—is extended across the shaft to form an operating arm 119. As shown in Figure 6 there is connected to this arm by a pin 120 a cam rod 121 extending through the table toward the main shaft and carrying upon its lower end a cam roller 122 operated by the annular cam 64 secured to the face of a rack disc 62 (see also Figure 8) secured upon the main shaft. Upon a pin projecting from the side of the cam rod is a presser arm 124. The presser arm is pivoted at its rear end to a bracket 125 depending from the rear edge of the table and intermediate its length is attached to a coil spring 126 for urging it downward.

Upper string gripper

At certain times, as when the needles are descending and when the knotters are tying the strings, it is necessary to hold the upper end of the strands. Means is therefore provided for gripping the strings being fed inward to the needles. The upper string gripping mechanism consists, as seen in Figures 6, 11 and 13 of a gripper bar 130 located immediately above the upper ends of the needles. The bar is slidably mounted upon curved rods 131 extending downward from the tie bar 108, and coil springs 132 mounted on these rods normally press the gripper bar downward into engagement with the upper ends of the needles in such manner that the strings are gripped between the bar and the needles.

At certain times it is necessary to release the incoming parts of the strings so means is provided for lifting the gripper bar from the needles. As shown in Figures 13 and 14, the front ends of lever 134 engage the ends of the gripper bar 130. These levers are rigidly mounted (see Figure 9) on the outer ends of the shaft 117 and are additionally connected together so as to act in unison (see also Figure 8) by a cross bar 135 connected to their rear ends. They are operated (Figs. 13 and 16) by a crank arm 136 rigidly secured to one of the levers, which crank arm is actuated by a gripper cam rod 137 pivoted at 138 to the end of the crank arm and provided at its lower end with a slot 139 embracing a bearing sleeve mounted on the main shaft beside the cam 69. At one end of the slot the push rod is provided with a cam roller 141 for engagement by the cam to raise the gripper bar.

It will be noted from Figure 16 that the cam 69 is of such a length and is so disposed on the main shaft that the string gripper will be lifted from the needles when the needles are rising and during such time as the strings are being pulled out to form lengths suitable for the tickets by the ticket pull grippers, later to be described. Further, the cam may be adjusted on the main shaft to regulate the timing of the string gripper.

The lower string gripper

After the needles have pierced the tickets and carried the free ends of the strings below the table top, it is necessary to have the ends of the strings held while the needles retract and also while the length of strings is being pulled out by the ticket feed gripper.

The mechanism for accomplishing this is best shown in Figure 15. A plurality of gripper fingers 145 are mounted on a corresponding number of arms 146 secured to a gripper shaft 147. The fingers are urged upwardly toward the lower surface of the table by springs 148 connected to the rear ends of the fingers and to the gripper arms 146. All of the arms are operated together by an arm 149 rigidly secured to the shaft 147 and operated by a cam push rod 150. This push rod is slotted at its lower end as at 151 to embrace the main shaft and at one end of the slot is provided with a cam roller 152 adapted to be engaged and periodically operated by the cam 68 adjustably mounted on the main shaft. The arm 149 is constantly urged downward by a coil spring 154. The gripper fingers 145 engage the loose ends of the strings beneath the table and press them against a side plate 155 of the main frame. The cam is so shaped as to cause the strings to be gripped for approximately a half revolution of the main shaft or perhaps somewhat less.

It is necessary to grip the strings by this mechanism continuously after the needles have inserted them through the table top until ends are cut off by the scissors after the knots have been formed. It is found more practical to use separate gripper fingers for each needle and string than a single bar extending across the machine to grip all of the strings together because with the separate grippers a knot or other inequality in one string will not prevent the grippers from properly holding the other strings.

Scissors

Means is provided for severing the strings toward the end of the knotting operation when the tickets are ready for removal from the machine. This means comprises a plurality of scissors, best shown in Figs. 11 and 12. The scissors comprise fixed blades formed by a series of projections 160 upon the upper edge of a plate 161 rigidly secured to the main frame. Cooperating with these projections is a plurality of movable scissors blades 162 pivoted to the plate 161 by pins 163 and all connected at their lower ends for simultaneous and collective operation to a gang bar 164 by pins 166.

As shown in Figure 9, an operating lever 165 is pivoted to the gang bar 164 and is oscillatable about a pivot formed by the extended enlarged end of one of the pins 166. The lever is operatively connected to a cam push rod 167 by a pin 168. The other end of the push rod is provided with a slot 169 embracing a scissors shaft 170. Adjacent each end of the slot the cam rod is provided with cam rollers 171 and 172 adapted to be operated by a cam 173 rigidly secured to the shaft 170. As shown in Figures 6 and 7, this shaft 170 is mounted in a long bearing 174 secured to the frame and is provided at its rear end with a bevel gear 175 driven by the bevel gear 67 on the main shaft.

It is to be noted that the arrangement of operating parts for the scissors is such that at the proper time the scissors are given a quick movement to cut the strings and remain in this posi-

tion until a later time when they are quickly moved to an open position. The friction of parts is sufficient to hold the scissors in the position to which they are moved.

15

Knotters

Various types of knotters might be used in the present machine but a specific type has been illustrated in the drawings to furnish a clear understanding of their operation in relation to associated mechanisms. These knotters are shown in assembly in Figs. 6, 7, 8, 9, 10, 11 and 13 and in detail in Figures 17 to 22. As illustrated there are twelve knotters corresponding to the twelve tickets of the strip.

The knotters comprise vertical spindles 180 mounted in spaced bearing plates 181, 182 and 183 secured to the main frame. The spindles are driven through gears 184 fast thereon meshing in pairs (Fig. 10) with gears 185 on stub shafts 186 mounted in the lower bearing plates 183 and 183a. At their lower ends the stub shafts, six in number, are provided with bevel gears 187 meshing with bevel gears 188 on a transverse shaft 189 mounted in bearings 190 secured to the main frame. At one end the shaft 189 is provided with a gear 191 which, as best shown in Figures 6 and 14, is adapted to be driven at intervals by an arcuate gear rack 192 secured upon the periphery of the disc 62 fast on the main shaft. Once during each revolution of the main shaft the arcuate rack comes into contact with the gear 191 and rotates the knitter spindles through one revolution. To insure meshing of the gears to avoid clashing and breakage of teeth the (see Fig. 14) disc 62 carries member 193 which comes into contact with an arm 194 fast on the gear shaft 189. These parts start the shaft 189 turning at exactly the proper time to mesh the gears.

At their upper ends the knitter spindles, as shown especially in Figures 13 and 17 to 22, are provided with spiral beaks 195 comprising (Fig. 20) upper jaws 196 and lower jaws 197. The lower jaw is normally urged against the upper by a coil spring 198 and at intervals is pulled away from the upper jaw by reason of a cam block 199 riding under an arcuate cam 200 secured to the bearing plate 181. The action of the cam opening the jaws will be quite apparent from Figures 17 to 22 and the period at which the jaws open will be explained later in connection with the operation of the machine. The spindles start from a position of rest in which the beaks point toward the front of the machine, as shown in Figure 17 and after rotation end up in about the same position or if they do not stop in this position due to the action of the driving elements, they will be pulled to this position by the strings when the tags are removed from the machine.

60

The string lift bar

Cooperating with the knotters (Figs. 11 and 13) is a notched string lift bar 205 disposed in front of the knotters as by being mounted on swinging arms 206 secured to the main frame by pivot bolts 207. One of the arms (Fig. 11) is provided with an integral extension 208 to which is pivotably attached a link 209. Adjustably secured to the lower end of the link by adjustable collars 210 is a fitting 211 provided (see Figure 14) with an actuating pin 212.

As shown in Figure 14 a lever 213 is connected to the pin 212 and to a fixed pivot 214 secured in a bracket 215 attached to the main frame. At its rear end the lever 213 is provided with a cam

roller 216 adapted to be actuated by the short cam 61 secured to the main shaft. A spring 217 normally urges the front end of the lever 213 upward to keep the lift bar in a lower position but upon actuation by the cam the bar is lifted upward and to the right, as viewed in Figure 11, so as to lift the strings when the knitter has completed part of a revolution to cause the ends thereof to align with and drop between the jaws of the beak of the knitter. The action of the knitter will be clearly understood from the above description by those skilled in the art and need not be considered further here but will later be considered in connection with the related operation of the several parts of the machine.

15

Ticket pull frame

Means is provided for moving the ticket grippers, shortly to be described, from a position near the main frame where they grip the ticket strips to an off position where tang-restoring members are located. This means comprises, as shown in Figures 2, 6 and 7 a pull frame including (Fig. 2) three spaced, curved bars 220 swingably mounted upon a pull frame shaft 221 extending transversely of the main frame.

25

The pull frame has two swinging movements during each cycle of operation of the machine. The first is to lengthen the strings attached to the ticket strips by pulling the strips away from the needles and the second is to cooperate with the knotters by first moving toward them to put slack in the strings and subsequently moving away from them to tighten the knots formed by the knotters. The first movement of the frame 35 for pulling out or lengthening the strings is of greater amplitude than the second and on this first backward movement the frame pauses long enough to allow the tang restorers to operate. The second outward movement is merely sufficient 40 to tighten the knots in the strings to get the pull frame spaced away from the main frame so that the sweep can operate between the two frames and remove the ticket strip.

35

In order to accomplish these two movements 45 it is found most convenient to employ two separate and distinct actuating means for the pull frame.

40

The first means, as shown in Figure 7, for accomplishing the longer movement comprises a 50 connecting rod 222 pivoted to the pull frame at one end and to a slotted arm 223 at the other end. The slotted arm constitutes part of a bell crank lever pivoted upon a transverse rod 224. The other arm 225 of the bell crank lever carries a cam roller 226 at its outer end adapted to cooperate with the cam 65 on the main shaft. A strong spring 228 urges the arm 225 upward and as a consequence tends to maintain the feed frame 55 in a position adjacent the needles on the main frame at all times when it is not positively urged away from the main frame by other means, one of which has just been described as including the cam 65 and related parts.

50

Alternating in action with the frame actuating means just described is another means which gives the second or shorter movement to the frame. This means which is also shown in Figure 7, comprises a cam arm 230 formed rigid with the pull frame which extends into proximity to the secondary shaft 53. The end of this arm is provided with a cam roller 231 adapted to be operated by the cam 73 mounted on the secondary shaft.

55

60

65

70

75

75

Strip grippers

As shown in Figures 7 and 13, the strip grippers comprise fixed jaws 235 (in the present machine, three) rigidly mounted on the pull frame and movable jaws 236 (also three) pivoted upon bearing pins 237 at the top of each of the pull frame bars 220. The upper or movable jaws 236 are provided with a cross-bar carrying a plurality of projecting hooked fingers 238 adapted to engage behind the rear edges of the ticket strips. The fingers 238 of the ticket grippers, as shown in Figure 13, are disposed in alignment between the needles of the machine not only for a purpose of clearing the needles but for the purpose of presenting the needle-pierced portion of the tickets to the tang restoring means.

Referring to Figures 6 and 7, the movable jaws 236 of the gripper are actuated by push rods 239 pivoted to extending ends of the jaws and connected at their lower ends by pivots 240 to oscillating arms 241 pinned to the pull frame upon a rock shaft 242. Another arm 243 carries a cam roller engaged by the curved arm 244 of a cam lever 245. The cam lever is pivoted upon a journal 246 secured in the upper end of the pedestal 247 mounted on the base of the machine. The cam lever is curved at its lower end to cooperate with the cam 74 mounted on the secondary shaft, a cam roller 248 being provided on the end of the cam lever for this purpose.

It will be noted from Figure 7 that the curved cam 244 is formed as an arc of a circle concentric with the pull frame pivot 221 when the cam roller is riding upon a concentric portion of the cam 74. By this arrangement the cam lever holds the jaws of the strip grippers open by a constant width while the pull frame is oscillating during such time as the concentric portion of the cam 74 is acting upon the cam lever. A raised portion 74a of the cam, however, is made sufficiently high to open the jaws more than normal when the tang restoring punches operate and the strip is released for removal. Springs 249 disposed between a fixed part of the frame and the movable jaws of the strip grippers serve to keep the jaws closed except when positively opened.

Leaf springs are provided on the pull frame adjacent the gripper jaws for holding the strips firmly against the hooked ends of finger 238 and for expelling the ticket strips from the jaws when released. These springs are relatively light and are pushed back by a fixed part of the main frame when the gripper jaws move forward to engage a strip.

Tang restorers

If the tickets employed have clear holes through them for the strings the mechanism now to be described is not required. But if no clear holes are provided, the needles will form tangs or burrs of material when they pierce the tickets. Preferably the tickets are cut along predetermined lines to control the shape and disposition of the tangs. In the present instance particular reference will be made to tickets having V-shaped cuts wherein the needles push out from each ticket a single V-shaped tang.

When these tangs are pressed back into the plane of the tickets at least two desirable results are accomplished. First, more writing surface is provided on the tickets than would be if clear holes were used and second, the tangs grip the strings and cause them to maintain the strings in a definite relationship with the tickets so the tickets may be readily passed through apparatus

such as printing machines which perform a subsequent operation on the tickets.

This mechanism is best shown in Figures 1, 2, 3, 6 and 7. Noting especially Figure 7, there are a plurality—one for each ticket—of anvil levers 260 pivoted on rock shaft 261 (discontinuous for gripper jaw movement) supported by depending brackets 262. Cooperating with the anvil portions of the levers 260 are a corresponding number of punches 263 mounted on a punch-bar 264.

The levers 260 are operated by connecting rods 265 (twelve in number) adjustably connected to the levers 260 by nuts 266, springs 267 being interposed between the levers and rods to absorb excess movement of the punches. The rods are connected at their lower ends to a cross-bar 268 secured to toggle arms 269 which are pivoted to upstanding bracket 270 and which cooperate with associated toggle arms 271 similarly mounted on brackets 270. The toggle arms are connected by slot and sleeve joints 272 and are held in proper spaced relation by a cross-bar 273. The arms 271 are provided with cam rollers 274 through which the toggle arms are operated by the cams 71 on the secondary shafts.

The punch bar is connected by guide rods 276 with an upper bar 277, the outwardly protruding ends of which are attached to push rods 278 attached at their lower ends to the sleeves forming part of the slot and sleeve points 272. The rods are guided by brackets 279 secured to the base and are constantly urged upward by springs 280 pressing against the brackets 279 and the adjustable collars 281 on the rods.

Sweep

The means for removing ticket strips from the machine comprises, as shown in Figures 1 to 4, a sweep 285 mounted upon an oscillating shaft 286. The sweep is sufficiently long to reach across the full length of a ticket strip and brush it from between the main frame and ticket gripper jaws when completed. The heel of the sweep engages the string of the end ticket and pushes it into the groove or space 287 between plates 288, 289 secured by screws and spacers 290 to a board 291 attached to the main frame. The groove is flared at its receiving end and the sweep is specially shaped to engage the string, which is disposed near the mouth of the groove, to sweep it thereinto. The knots of the strings of the end tag of each strip, are disposed on the opposite side of the plates 288, 289 from the ticket strips and thus support the strips for sliding movement along the groove. The strips may be removed from the outer end of the groove in required amounts.

As best shown in Figures 11 and 13 the sweep shaft 286 is attached by a nut 292 to a guide member 293 and the hub of the sweep is rigidly attached to a pinion 294, both the gear and sweep being loose on the shaft.

Referring to Figure 11, a rack 295 is slidably mounted in the guide member 293 so as to actuate the pinion 294. At its upper end the rack is attached to an operating rod 296 extending downward (Fig. 16) into operating relationship with the sweep cam 72 on the secondary shaft. To guide the rod, a slot 297 is provided on its lower end embracing the secondary shaft. A cam roller 298 mounted above the slot cooperates with the cam 72. A coil spring 299 attached to an arm 300 adjustably mounted on the rod and to a fixed part of the main frame tends to keep the roller 298 in engagement with the cam and the sweep in its normal raised position.

Counting mechanism

As seen in Figures 1 and 3 the main shaft carries at the right-hand end a worm 305 driving a worm gear 306 rotatably mounted on a shaft 307. The shaft is rigidly attached to a bell bracket 308 and at its outer end supports a bell 309. A bell striker 310 is pivoted upon a pin 311 and (Figure 5) is urged downward by a spring 312. A trip cam 313 attached to the striker and positioned in the path of a cam pin 314 actuates the striker once for every given number of revolutions of the main shaft, which is also an indication of the number of ticket strips produced since a complete cycle is produced by each revolution of the main shaft.

Operation

In describing the operation attention will be focused upon the ticket strip, which will be followed throughout the several operations performed upon it, rather than upon the machine parts; although it is to be noted that while only one ticket strip is produced for each cycle of the machine, there is one time at least when two tickets strips are being operated upon simultaneously but by different mechanisms.

Assuming the feed slides 88 to be in rearmost position with suction existing at the openings 81 which are located directly beneath the stack of ticket strips in the guides 79, the lowermost strip will be pulled down at each end tightly upon the feed slides and at the next forward movement of the slides will be pushed forward. The rear edge of the strip which is cut or notched for passage of the needles comes directly beneath them. The wedge 69 raises the clamp strap 101 to permit the strip to move forward. The fingers 103 on the strap prevent return movement of the strip with the suction feed slides when the wedge again lowers the strap and fingers.

While the ticket strip is held by the feed slides in this forward position the needles 105 are moved rapidly downward to pierce the tickets and carry the string ends through them. As seen in Figure 6, the needle operating cam roller 122 at this time rides up on the highest portion of the needle cam 64 to push the ends of the needle below the lower surface of the frame table 22.

The ends of the strings protrude some distance below the ends of the hollow needles and the lower gripper fingers 145 sweep across the under surface of the table after needles have moved up slightly (see the lowered cam surface of cam 64 in Figure 6) and grip the string ends by pressing them individually against the frame side plate 155. Referring to Figure 15, the cam 68 holds the lower grippers in this position until knots have been tied in the strings.

During the downward movement of the needles the upper string gripper bar 130 grips the strings tightly upon the upper ends of the needles to pull out more length from the source of supply. When the needles are again in their highest position the gripper 130 is raised to allow the strings to be pulled out through the needles from the source of supply. The cam 69 (Figure 16) will then be in proper position to accomplish this. The gripper is held in raised position until the ticket grippers on the pull frame have pulled the strings out to the full length required. Compare the position on the main shaft of cam 69 in Figure 16 which holds the upper string grippers in more gripping position and cam 65 in Figure 6 which hold the pull frame in the position remotest from the needles.

During the time the needles are moving upward the pull frame with the ticket grippers is moving toward the needles. Note (Figure 6) that the pull frame cam roller 231 is about to ride off the high part of cam 73 to allow the frame to move toward the needles under the action of spring 228.

Referring to Figure 7, the ticket gripper jaws remain open until the frame is up to the needles and the jaws have embraced the ticket strip. Then the jaws close upon the ticket strip due to the cam roller 248 riding off the high position of cam 74 on the secondary shaft. Note from the position of the needle cam 64 in Figure 6 that the tickets are gripped while the needles are down through the tickets. The ticket gripper jaws thereafter remain closed until the strips are ready for removal from the machine.

The cams 65 on the main shaft next moves the pull frame to extreme position away from the needles. In this position the cams 71 push the toggle arms downward to bring the punches 263 and anvil levers 260 together to restore the tangs pushed out by the needles into the planes of the tickets.

While the tickets are still held in off position the needles move down a slight distance to place the string strands in the path of the knotted beaks. Note the long moderately raised portion of the needle cam 64 in Figure 6. The knotted spindles are started into operation by the arcuate rack 192 on main shaft 62 coming into engagement with the knotted actuating pinion 191, associated parts 193, 194 already described being active at this time for absorbing shock to prevent breakage of the gear teeth.

As the knotted begin to rotate to form loops in the strings the pull frame begins to move toward the knotted 195 the other ends of the strings still being held by the upper and lower string grippers to give slack to the double strands of strings.

During the time the knots are being formed the string lift bar 205 is appropriately moved by the cam 61 to cooperate with the knotted. Also toward the end of the movement of the knotted the scissors are operated by the scissors cam 173 to sever the gripper-held ends of the strings.

Finally the pull frame retracts from the knotted to pull the knots tight. Then the ticket gripper jaws open and the sweep moves downward across the string strands to pull them from the jaws of the knotted and remove the ticket strip to the suspension groove as already described.

While the invention has been particularly described with reference to one specific embodiment thereof it is to be understood that no limitations are imposed thereby and that the invention is only to be measured by the scope of the subjoined claims.

I claim as my invention:

1. Apparatus for stringing a plurality of tickets of a strip of tickets comprising in combination, means for moving a strip of tickets to an operating position, needles for inserting strings in said tickets at operating position, means gripping said strings to said needles on downward movement to pull out strings from a source of supply, means for gripping the ends of said strings when inserted through said tickets, means including a swinging frame and ticket grippers for grasping said strip and pulling it away from said needles, means for actuating said frame to move it a maximum distance from said needles means for restoring tangs made in the tickets when the frame is in extreme off position, means for tying knots in

- 5 said strings, said frame moving back to allow slack in said strings for said knotters, means to move said frame away again but a shorter distance to tighten said knots, means to sever said strings, and means to sweep said strip of tickets from said knotters and strip grippers onto a fixed rack.
- 10 2. Apparatus of the character described comprising in combination, means for inserting strings in a strip of tickets, a fixed rack provided with a string receiving groove, means for pulling the strings out to proper length from the source of supply after insertion in the tickets, and means striking the string strands for sweeping all of the tickets of a strip out of the machine and engaging the string of one ticket in the groove of the fixed rack when the stringing operation is completed, said means including an oscillatory sweep secured to a pinion on a shaft, a rack meshing with said pinion and a cam for actuating said rack.
- 15 3. Apparatus of the character described comprising in combination, means for inserting strings in a strip of tickets, a fixed rack provided with a string receiving groove, means for pulling the strings out to proper length from the source of supply after insertion in the tickets, and means striking the string strands for sweeping all of the tickets of a strip out of the machine and engaging the string of one ticket in the groove of the fixed rack when the stringing operation is completed, said means including an oscillatory sweep.
- 20 4. Apparatus of the character described comprising in combination, means for inserting strings in a strip of tickets, a fixed rack provided with a string receiving groove, means for pulling the strings out to proper length from the source of supply after insertion in the tickets, and means striking the string strands for sweeping all of the tickets of a strip out of the machine and engaging the string of one ticket in the groove of the fixed rack when the stringing operation is completed.
- 25 5. Apparatus of the character described comprising in combination, means for piercing a plurality of tickets of a strip of tickets for inserting strings therein, said piercing means forming tangs on said tickets, and means for restoring said tangs into the plane of the tickets, said means including converging punches and anvil levers, toggle levers operatively connected to said punches and anvil levers, and cams for actuating said toggle levers.
- 30 6. Apparatus of the character described comprising in combination, means for piercing a plurality of tickets of a strip of tickets for inserting strings therein, said piercing means forming tangs on said tickets, means including a movable frame for moving said tickets from said piercing means, and cooperating punches and anvil levers mounted upon a fixed frame converging together upon said tickets to restore said tangs when said frame is in a position remote from said piercing means.
- 35 7. Apparatus of the character described comprising in combination, means for piercing a plurality of tickets of a strip of tickets for inserting strings therein, said piercing means forming tangs on said tickets and means for restoring said tangs into the plane of the tickets, said tang-restoring means including punches and anvil levers converging together upon said tickets.
- 40 8. Apparatus of the character described comprising in combination, means for piercing a plurality of tickets of a strip of tickets for inserting strings therein, said piercing means forming tangs on said tickets and means for restoring said tangs into the plane of the tickets, means for restoring said tangs into the plane of the tickets.
- 45 9. Apparatus for stringing tickets comprising in combination, means for inserting strings through a plurality of tickets and means for moving said tickets away from said inserting means including a swingable frame, a plurality of ticket gripper jaws mounted on said frame, and means for operating said jaws independently of the movement of said frame, said jaw-operating means including a cam lever, a cam for operating one end of the lever and a jaw operating cam arm at the other end of said lever which is concentric with the pivot center of said frame when the cam actuated end of said lever is riding on a concentric portion of said cam.
- 50 10. Apparatus for stringing tickets comprising in combination, means for inserting strings through a plurality of tickets in a strip and means for pulling the tickets out to lengthen the strings, including a pull frame movable perpendicularly to the length of the strip to dispose the strings attached to the tickets in parallel relationship, and means including two separately acting cams for moving said frame away from said string-inserting means twice during the stringing operation for each strip of tickets, and resilient means constantly urging said frame toward said string-inserting means.
- 55 11. Apparatus for stringing tickets comprising in combination, means for inserting strings through a plurality of tickets and means for pulling the tickets out to lengthen the strings, including a pull frame, and means including cams on each of two separate cam shafts for moving said frame forward and backward twice during each cycle of the apparatus.
- 60 12. Apparatus for stringing tickets comprising in combination, means for inserting strings through a plurality of tickets and means for pulling the tickets out to lengthen the strings, including a pull frame, and means for moving said frame forward and backward twice during each cycle of the apparatus.
- 65 13. Apparatus of the character described comprising in combination, means to insert strings through a plurality of tickets in a strip of tickets means to pull said strings out to proper length from the source of supply after insertion in the tickets, means to tie knots in said strings comprising rotary beaks, a swingable knotter bar for raising strings to cooperate with said beaks, said bar being pivoted at each end to swinging arms, a connecting rod for actuating said arms, a pin supported upon a fitting adjustable by collars on said rod, a cam lever for actuating said pin and associated parts and a spring normally urging said bar to lowermost position.
- 70 14. Apparatus of the character described comprising in combination, means to insert strings through a plurality of tickets in a strip of tickets means to pull said strings out to proper length from the source of supply after insertion in the tickets, means to tie knots in said strings comprising rotary beaks and a swingable knotter bar for raising and swinging said strings to cooperate with said beaks.
- 75 15. Apparatus of the character described comprising in combination, means to insert strings through a plurality of tickets in a strip of tickets, means to pull said strings out to proper length from the source of supply after insertion in the tickets and a plurality of knotters for tying knots in said strings when pulled out, said knotters each including a rotatable spindle, a gear thereon a

shaft for rotating said knotted spindles, a gear on said shaft, a rotatable segmental rack for rotating said gear and means for meshing said rack and gear.

5 16. Apparatus of the character described comprising in combination, means to insert strings through a plurality of tickets in a strip of tickets, means to pull said strings out to proper length from the source of supply after insertion in the tickets and a plurality of knotters for tying knots in said strings when pulled out, said knotters each including a rotatable spindle, a gear thereon, a stub shaft geared to each two of said knotter spindles, and means to drive said stub shafts at intervals, including a transverse shaft having a plurality of bevel gears meshing with bevel gears on said stub shafts.

10 17. Apparatus of the character described comprising in combination, means to insert strings through a plurality of tickets in a strip of tickets, means to pull said strings out to proper length from the source of supply after insertion in the tickets and a plurality of knotters for tying knots in said strings when pulled out, said knotters each including a rotatable spindle, a gear thereon, a stub shaft geared to each two of said knotter spindles, and means to drive said stub shafts at intervals.

15 18. Apparatus for stringing a strip of tickets comprising in combination, needles for inserting strings through a plurality of tickets and through a supporting table, a plurality of fingers spring-pressed upward against said table, arms pivotally

supporting said fingers a side plate, and means for moving said fingers collectively to grip said strings against said side plate.

19. Apparatus for stringing a strip of tickets comprising in combination, means for presenting a strip of tickets to an operating position, a plurality of tubular needles separately clamped to a needle bar, a second bar connected to said needle bar by tubular spacers, fixed rods on which said tubular spacers slide, pins at the ends of said bars, slotted arms operatively engaging said pins, a rock shaft for said arms, a cam arm secured to one of said slotted arms, a cam rod pivoted at one end to said cam arm and actuated at the other end by a rotary cam, and means biasing said cam rod toward said cam.

20 20. Apparatus for stringing tickets comprising in combination, means for holding a strip comprising a plurality of tickets in a horizontal position, means for inserting strings through the several tickets of the strip, means for moving said strip of tickets away from its original position to a new position where the edges of the strip are parallel to their original position, said means including a swingable frame mounted on a horizontal shaft and movable in a direction at right angles to the length of the strip to pull out the strings attached to the tickets in parallel relationship, a plurality of ticket gripper jaws mounted on said frame, and means for operating said jaws independently of the movement of said frame.

JACOB F. GRAEBER.
